UNITED STATES PATENT OFFICE.

WILLIAM E. SPARKS, OF NEW BRITAIN, CONNECTICUT, ASSIGNOR TO
P. & F. CORBIN, OF SAME PLACE.

LATCH.

SPECIFICATION forming part of Letters Patent No. 279,837, dated June 19, 1883.

Application filed February 5, 1883. (Model.)

To all whom it may concern:

Be it known that I, WILLIAM E. SPARKS, of New Britain, in the county of Hartford and State of Connecticut, have invented certain 5 new and useful Improvements in Latches, of which the following is a specification.

My invention relates to improvements in that class of latches which are commonly called "anti-friction," from the fact that the latch 10 is provided with a lever or swinging cam, to cause the latch-bolt to be forced inward smoothly and easily under the influence of the striker; and the objects of my invention are to so hang the swinging cam-lever that the pin- 15 and-slot connection thereof may be between the cam-lever and latch-bolt, and so that the cam-lever may be made with trunnions formed integral therewith, and so that the support for one trunnion or pin of the said lever may 20 be formed on the broad side of the latch-case instead of the face-plate. I attain these objects by the construction illustrated in the accompanying drawings, in which—

Figure 1 is a front elevation of parts of my 25 latch with the cap-plate removed. Fig. 2 is a horizontal sectional view of my latch on line xx of Fig. 1, and showing the parts which are above said line. Fig. 3 is a like view of my latch as adapted for a left-hand door. Fig. 4 is a side view of the cam-lever, and Fig. 5 is 30 an edge view of the same.

A designates the latch-case; B, the cap-plate; C, the face-plate; D, the latch-bolt, and E the cam-lever. These parts, when considered independently of certain features of construction hereinafter particularly pointed out, 35 are old, and are hereby disclaimed.

The mechanism for drawing the latch-bolt into the case by means of the knob-spindle 40 may be that of any ordinary construction.

In the prior construction of the latch-case, latch-bolt, and cam-lever, the latch has been pivoted or hinged to a lug or lugs on the face-plate, said lugs and one corner of the cam-lever being drilled and secured together by a pin, and the other corner of the cam-lever has 45 been connected with the latch-bolt by a pin-and-slot connection. I form the cam-lever with rigid trunnions a a' , projecting from its opposite sides at the two pivotal corners, as shown most clearly in Figs. 4 and 5, and I prefer to form said trunnion integral with said cam-lever. One of these trunnions, a , is received in a hole drilled in the side of the latch-

bolt head, as indicated by the broken circle 55 in Fig. 2. The other trunnion, a' , lies within a slot or recess formed in the lug b , cast or otherwise formed on the broad side of the latch-case A, and is confined therein by the cap-plate C. When the latch-bolt is extended 60 the edge of the cam-lever, which slightly projects beyond the sides of the trunnion a' , comes into contact with the cap-plate, and the slot or recess for the trunnion is deep enough and wide enough to allow the trunnion to move 65 inward and backward a little, far enough to allow the cam-lever to swing freely as the latch-bolt moves inward, without any tendency to throw the bolt sidewise. Thus it will be seen that what may be termed the 70 "pin-and-slot connection" is made between the cam-lever and the latch-case.

For a left-hand latch the same general construction is followed, except that the lug b' is shorter, as shown in Fig. 3, and in order to 75 have the cap-plate C confine the trunnion, a lug or projection, c , is formed on the cap-plate.

By my improved construction the trunnion a' is brought nearer to the side of the latch-case than in the prior construction, having the pivoted lug on the face-plate, and the trunnion moves in the slot or recess in unison with the movement of the cam-lever, instead of in the opposite direction, and thereby it is 80 believed that my device works much more smoothly than in the prior construction. By forming the trunnion-recess in lugs on the broad side of the latch-case instead of on the face-plate, I am enabled to form the trunnion-recess by casting, to form solid trunnions on the cam-lever, to avoid drilling and fitting for the trunnion, and to more readily put the latch into the case and take it out when desired, as the same can be done with- 90 out the employment of any separate and independent pin.

I claim as my invention—

In a latch having the pivoted cam-lever, the lug formed on the broad side of the latch-case, and having the trunnion slot or recess in its edge, the cam-lever being provided with the rigid trunnion a' , which is confined within said recess by the cap-plate, substantially as described, and for the purpose specified.

Witnesses: WILLIAM E. SPARKS.
